(57) **CLAIM**

The ornamental design for a bottle spout, as shown and described.

DESCRIPTION

FIG. 1 is a top perspective view of a bottle spout showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top perspective view of the bottle spout of FIGS.

1-7 shown in the environment of a bottle;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a top perspective view of the bottle spout of FIGS.

1-7 shown in the environment of a different bottle;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top plan view thereof; and,

FIG. 21 is a bottom plan view thereof.

The broken line showing of the pull tab, threads, cap threads, portions of the base of the bottle spout, the bottle base, the bottle cap, the central portion of the bottle, in relevant drawings shows unclaimed subject matter for the design in those drawings.
